UNITED STATES PATENT OFFICE.

BERNIE G. PRIMROSE, OF PLEMONS, TEXAS.

DEEP-WELL PUMP.

Application filed September 2, 1926. Serial No. 133,226.

This invention relates to improvements in deep well pumps of the type utilized in the lifting of crude oil.

The object of this invention relates principally to means for increasing the inlet by the application of plate valves in lieu of the conventional ball and seat and the elimination of the tendency of the cage which is essential in the ball type of valve to mud up, by the provision of spaced stud bolts which act as guides for the plate valve.

Another object resides in the use of a rubber packing of the form common in the swab art in place of the usual cup packer, wherein by the destruction of the working barrel by the sand is avoided.

Other objects will more clearly herein-after appear by reference to the accompanying drawings forming a part of this specification and wherein like characters of reference designate corresponding parts throughout the several views, in which:

Figure 1 is a side elevation, partly in section;

25 Figures 2, 2^a, 2^b, show an enlarged sectional view in group form to permit the illustration of the entire assembly;

Figure 3 is a section on line 3—3 of Figure 1;

30 Figure 4 is a section on line 4—4 of Figure 1; and

Figure 5 is a section on line 5—5 of Figure 1.

Referring more particularly to Figure 2, the working barrel is shown positioned within the casing and having its working face flush with the inner face of the casing by means of the joint collar A which is provided with the threaded off-set portion *a* which accommodates the casing section B as well as the working barrel C. The working barrel C and the casing section B are threaded together at their extremities and the casing in turn is threaded into the off-set portion of the collar A by means of screw threads *b*. A metallic washer D is positioned between the adjacent ends of the working barrel and the ends of the casing sections E. The piston assembly is of the multiple type in that it involves two or more elements operably associated and each involving the essential packing and valve mechanism. Each of these piston elements is substantially identical and accordingly a description of one will suffice for the purpose of illus-

trating the plurality utilized in the entire piston.

Referring now to the first section of the illustration in Figure 2, the connecting rod is shown internally threaded into the swedge 60 nipple F formed with the spaced discharge ports *f*. The lower end of this nipple F is approximately the diameter of the working barrel and is internally threaded to receive the upper threaded end of the metallic piston section G, which is provided with a central passageway *g* into which is threaded the pipe connection H. The lower end of this pipe H is externally threaded and is spaced from the upper piston section G a sufficient 65 distance to permit the arrangement of the packing rubber I, which is of the swab type. A lower metallic piston member J is threaded onto the lower end of the pipe section H and abuts against the lower end of the packing rubber I. A set screw as shown at *h* may be used for locking the packing sections G and J onto the extremities of the pipe section H. 70

The upper end of the piston section G is 80 threaded at diametrically opposite points to receive the stud bolts K which act as guides for the plate valve L, shown more clearly in the illustration in section at Figure 5. In this illustration the valve is shown to include oppositely extending perforated ears through which the stud bolts K extend and by means of which the valve is guided in its movement from the seat formed at the upper edge of the externally threaded pipe section 90 M. This pipe section M is threaded into the upper extremity of the passage formed in the piston section G and extends beyond the upper surface of the latter a substantial distance. The contacting face between the valve 95 seat and the valve may be bevelled as shown to secure a more perfect seating of the moving element.

The swedge nipple N which forms the connection between the upper piston element and the lower piston element is substantially identical with the nipple F but is not provided with ports corresponding to the ports *f* in the upper nipple. The valve member and the piston assembly is substantially identical. 100

A valve corresponding to the valves herefore noted is provided at the upper end of the casing section connecting the lower end of the working barrel, as shown at P, and 110

a similar valve Q, as shown in the last section of the disclosure of Figure 2^b, is placed at the bottom of the tubing and operates in the nature of the conventional foot valve.

5 The entire assembly is clearly obvious by an examination of Figure 1 and the function and operation of the various parts will be more clearly seen from this illustration.

Having thus described my invention, 10 what I claim as new and useful and desire to secure by Letters Patent, is:

1. In a deep well pump, a reciprocating member including connected pistons, each of said pistons including spaced metallic 15 sections, one of which is provided with a flat reciprocating valve and a cylindrical rubber between said sections.

2. The substance of claim 1 characterized in that the plate valve is carried at the upper 20 extremity of each piston and is limited and guided in movement by a pair of ears engaging spaced studs.

3. The substance of claim 1 characterized in that the plate valve is carried at the upper 25 extremity of each piston and is limited and guided in movement by a pair of spaced studs, the plate valve seating on a cylindrical valve seat, the seating face of which is spaced from the piston.

20 4. The substance of claim 1 characterized in that a swedge nipple is connected to the upper end of each reciprocating member.

5. The substance of claim 1 characterized in that the spaced metallic sections are con-

nected by a pipe section on which is arranged the cylindrical rubber, and the cylindrical rubber is formed to coincide with the faces of the metallic sections. 35

6. The substance of claim 1 characterized in that the spaced metallic sections are connected by a pipe section on which is arranged the cylindrical rubber. 40

7. In a deep well pump, a reciprocating member comprising a pair of spaced cylindrical metallic members, a reduced pipe section connecting said cylindrical members, a cylindrical rubber section positioned on the pipe section, a reciprocating plate valve on the upper cylindrical member and having apertured ears and studs mounted in the upper face of the cylindrical member for supporting and guiding the plate valve by passing through said apertures. 45

8. The substance of claim 7 characterized in that the upper cylindrical member is provided with a cylindrical valve seat for the plate valve and the valve seat has its seating surface spaced from the upper face of the metallic member. 50

9. The substance of claim 1 characterized in that a swedge nipple is connected to the upper end of the upper metallic section and is formed with discharge ports, and a second swedge nipple connects the upper metallic section to the lower metallic section. 55

In testimony whereof I have affixed my signature.

BERNIE G. PRIMROSE.
